United States Patent Office

Des. 200,121
Patented Jan. 19, 1965

200,121

TRASH RECEPTACLE

Maurice C. Lumley, Cincinnati, Ohio, assignor to The F. H. Lawson Company, Cincinnati, Ohio, a corporation of Ohio

Filed Mar. 5, 1964, Ser. No. 78,893

Term of patent 14 years

(Cl. D58—17)

Fig. 1

Fig. 3

FIG. 1 is a side elevational view of a trash receptacle, showing my new design;

FIG. 2 is a front elevational view thereof;

FIG. 3 is a top plan view thereof.

The side not shown is substantially the same as the side shown in FIGURE 1 and the rear not shown is substantially the same as the front shown in FIGURE 2 except for the hinged door panel.

I claim:

The ornamental design for a trash receptacle, as shown and described.
